UNITED STATES PATENT OFFICE.

ANTONIO MARCANTE, OF MANVILLE, RHODE ISLAND.

REED FOR LOOMS.

No. 874,096.

Specification of Letters Patent.

Patented Dec. 17, 1907.

Application filed November 21, 1906. Serial No. 344,485.

To all whom it may concern:

Be it known that I, ANTONIO MARCANTE, a subject of Italy, residing at Manville, town of Lincoln, in the county of Providence and State of Rhode Island, have invented certain new and useful Improvements in Reeds for Looms, of which the following is a specification, reference being had therein to the accompanying drawing.

10 This invention relates to the construction of reeds for looms and has for its object to construct a reed having some of its dents provided with an outwardly extending foot adapted to project across the upper face of 15 the lay and form a grating of parallel bars between which the warp thread may lie and over which the shuttle may pass without coming in contact with said threads as it is being thrown across the loom.

20 As is well known to those skilled in the art the ordinary method of weaving is to pass the shuttle through the open shed where it rides directly on the lower warp threads, and it is found in practice that in the weaving of 25 silk and other fine threads, as the shuttle is thrown back and forth across the lay it has a tendency to roughen up the fibers, and sometimes breaks the delicate threads as it comes in contact with them. To obviate 30 this difficulty I have provided a reed constructed as above described with outwardly extending parallel members which allows the said threads to pass through the reed in the usual way. When the shed is open these 35 threads pass down between and lay beneath the upper edges of these extensions which then form a bridge or grating over which the shuttle may pass without coming in contact with these delicate threads. The dents that 40 have the extending portions may be placed at any desired intervals in the reed. The shanks of said dents to which these extensions are attached are similar in construction to the ordinary dent and are secured to the 45 reed in the usual manner like the rest of the dents.

It is also found in practice that when the shuttle is driven rapidly across the loom it sometimes has a tendency to rise and engage 50 the upper threads of the shed and often leaves its path entirely and flies out of the loom. To obviate this difficulty I have also provided extensions on some of the dents to project outward from the upper edge of the 55 reed, thus forming two sets one above and one below the path of the flying shuttle and

when the shed is open the warp threads are drawn into the spaces between the extensions so that it is impossible for them to be touched by the shuttle in passing on its way 60 through the shed.

The invention is fully set forth in this specification and more particularly pointed out in the appended claims.

In the accompanying drawings: Figure 1— 65 is an elevation, looking at the end of a loom and showing some of the parts in section. Fig. 2—is a perspective view showing a portion of a reed and representing the dents that have the outwardly extending feet arranged 70 at intervals throughout the length of the reed. Fig. 3—is an enlarged detail of a dent provided with the extending foot. Fig. 4— 75 is an end view showing a number of the extensions and the connecting rod passing through said ends by which they are supported and also showing the collars or spacers between said ends which prevent them from moving on the said rod. Fig. 5—is a side elevation of a washer or spacer in section. 80

Referring to the drawings, at 1 is the usual breast beam at the front of the loom. 2 is the yarn beam and 3 the lay. On this lay is mounted the reed 4 in the usual way. The essential feature of this invention lies in the 85 construction and arrangement of the reed dents. Some of these dents are provided with an extension or finger 5 projecting outwardly and at right angles to the shank 6 and near one end thereof. The outer end of 90 this extension is nicely rounded over and has a downwardly extending portion 7 which portion is provided with a hole 8. These dents with their extensions are placed at intervals throughout the length of the reed 95 some being at the lower edge of the same and some at the upper edge of the reed to better control the direction of the shuttle. These extensions may be placed on all of the dents in the reed if desired, but on very fine reeds 100 such as that used in the weaving of silk, it is not found necessary to have these dents extend oftener than on every fourth or fifth dent and those extending from above need not be as close together as those below as 105 they have less work to do. The outer ends of these extensions are all bound together by a stay rod 9 that passes through the eye 8 in each, said rod also being threaded through a collar or spacer 10 which is placed between 110 the ends to hold them parallel and in the desired position. The extension at each end of

the reed may be supported from the lay by dropping down into a notch in said lug as shown at 11 in Fig. 4, thus nicely supporting the whole against the action of the flying shuttle.

The loom to which my improved reed is attached works in the ordinary way, the heddles 12—12 serve to spread the warp threads to open the shed and by their action the lower threads 16 are carried downward beneath the surface or upper edge 14 of the lower extensions 5—5. The upper threads of the shed are in like manner carried above the lower edges of the upper extensions 17 where the shuttle cannot come in contact with them even though it should rise and run along in contact with the lower edges of said extensions. While the threads lay in this position the shuttle 15 is thrown across the lay riding on this bridge or grating formed by these edges which carry said shuttle entirely clear of both threads of the shed.

The device is simple and practical in construction and accomplishes the object for which it is designed.

Having thus described my invention, what I claim as new and desire to secure by Letters Patent, is:

1. A reed for looms comprising a plurality of rigidly supported dents, a number of said dents being each provided with an integral arm extending at approximately right angles therefrom and arranged to form a grating, a supporting rod passed through the outer

ends of said arms, and means for maintaining uniform-spaces between the outer ends of said arms.

2. A reed for looms comprising a plurality of dents, a number of said dents being each provided with an integral arm extending at approximately right angles therefrom, said arms being arranged in sets, one set being located adjacent the top of the reed and the other set adjacent the bottom of the reed, and supporting rods passed through the outer ends of each set of arms.

3. A reed for looms comprising a plurality of rigidly supported dents, a number of said dents being each provided adjacent one end with an integral arm extending at right angles therefrom and arranged to form a grating, and means for preventing lateral movement of the outer ends of said arms.

4. A reed for looms comprising a plurality of dents, a number of said dents being each provided adjacent one end with an integral arm extending at right angles therefrom, said arms being arranged in sets, one set being located adjacent the top of the reed and the other set adjacent the bottom of the reed, and means for preventing lateral movement of the outer ends of said arms.

In testimony whereof I affix my signature in presence of two witnesses.

ANTONIO MARCANTE.
